UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

CUSHION.

No. 884,709.

Specification of Letters Patent.

Patented April 14, 1908.

Application filed May 1, 1906. Serial No. 314,658.

To all whom it may concern:

Be it known that I, EDWARD G. BUDD, a citizen of the United States, residing at Philadelphia, in the county of Philadelphia and State of Pennsylvania, have invented certain new and useful Improvements in Cushions, of which the following is a specification.

This invention relates to cushions and has reference more particularly to those of the 10 type commonly employed in car-seats.

The object of the invention is to provide a cushion having a metallic frame the parts of which are so formed as to give the desired curvature to the surface material of the 15 cushion.

In the preferred embodiment of my invention, the frame of the cushion is of rectangular shape, and comprises two or more frame-sections secured together at their ends. 20 These frame-sections are formed of sheet-metal pressed to the desired shape, and there may be four of them or, if desired, two, one of which is bent to form the top and end members so as to provide rounded corners at 25 the top of the cushion. To each of the end members of the rectangular frame so formed, I secure a sheet-metal form-piece and this piece is so constructed as to give to the covering material of the cushion the shape desired for the completed cushion. Thus, if 30 the cushion is to be used as a seat-cushion or as a back-cushion in a car-seat of the "turn-over" type, each of these form-pieces is so constructed that one edge thereof can be 35 readily secured to an end member of the frame and at the other edge a flange is provided turned inwardly of the frame. If the cushion is to be used as a back-cushion for a seat of the "walkover" type, each of the 40 form-pieces is constructed with inwardly turned flanges at both edges and is secured to the frame intermediate of these flanges. In both cases the distance between the line of attachment of the form-piece to the frame 45 and the flange, or flanges, varies throughout the length of the form-piece so that the flange is curved relatively to the plane of the cushion. In cushions as ordinarily constructed with a surface presenting a single 50 convex curve, the form-pieces will be of greatest width at a point adjacent to the centers thereof and will taper from their point to both ends; in cushions for the backs of car-seats having a head-roll, the form- 55 pieces will each have a point of greatest

width and will taper in both directions from this point and near the upper end will increase in width again so as to give to the covering material the small curved portion constituting the head-roll above the larger 60 curved portion constituting the body of the cushion.

I have illustrated the preferred embodiment of my invention in the accompanying drawings in which

Figure 1 is a front view of a back-cushion for a car-seat broken away and sectioned in part; Fig. 2 is a similar view of the end of the cushion, Fig. 3 is a section through one end of the cushion and Fig. 4 is a view similar to 70 Fig. 3, illustrating a modification.

Referring to these drawings, the cushion-frame consists of a plurality of sheet-metal frame-sections pressed to the desired form and secured together at their ends. The 75 cushion illustrated is adapted for use as a back-cushion for a car-seat of the "walk-over" type and the frame therefore consists of two frame-sections, one, indicated by the numeral 1, forming the bottom of the frame 80 and the other, 2, bent to form the top and ends, the bends being curved so as to provide rounded corners at the top of the cushion. The frame-sections are so formed as to facilitate attaching the covering material 85 thereto and this is preferably done by providing a groove in each frame section such that when they are assembled, there is a groove running around the entire periphery of the frame. In this peripheral groove is inserted 90 a tacking strip 3 of wood or of some fire-proof material such as paper fiber. The strip may be held in place by wedging it in its groove or by tacks 4 extending through holes provided in the metal. In order to stiffen the 95 frame, I prefer to provide one or more channeled cross-braces 5 extending across the frame and secured at their ends to the end members in any suitable manner, as by riveting them thereto. The member 1 forming the bottom of the frame and the portion of member 2 forming the top are preferably flanged inwardly of the frame as indicated at 100 6 and extending across the frame on both sides thereof in the cushion illustrated, but on only one side if only one side of the cushion is to be used, are a plurality of flat springs 7. These springs are secured at their ends to the flanges 6 by rivets 8.

Secured to each end of the frame is a me- 110

tallic form-piece 9. This is preferably a sheet-metal punching and is pressed to the desired form. At each edge is a flange 10 turned inwardly of the frame, the bend of the flange being a rounding one so that when the covering is drawn over it, it will lie smoothly thereon and there will be no sharp edge. The form-piece is secured to the frame in any suitable manner, preferably by riveting it to narrow flanges on the frame-section on either side of the groove for strip 3 as shown at 11, Fig. 3.

The shape of each of the form pieces 9 is such as will give to the ends of the completed cushion the desired curvature. Thus it will be seen from Fig. 2 that the distance between the flanges on opposite sides of the form-piece is greatest at a point near the middle of the length of the piece, preferably just below the middle, and from this point of greatest width the piece tapers off toward either end. When the covering material is drawn over a form-piece thus constructed it will present a convex surface of a curvature determined by that of the flange 10 lengthwise of the form-piece. The curvature of the form-pieces 9 is preferably somewhat less than that of flat springs 7 so that the surface of the completed cushion is convex both lengthwise and crosswise of the frame. When the cushion frame has rounded upper corners as shown in the drawings, the upper ends of the form-pieces 9 may be bent in to conform to the curvature of and lie close to the frame as indicated at 13, Fig. 1. The covering material may be secured to the frame over the springs and form-pieces in any suitable manner. In the drawings I have shown the form-pieces as provided with a central line of openings and when the covering material 14 is drawn taut, tacks 15 are driven through a beading 16, the covering 14 and the openings in the form-piece and into the tacking strip 3. The cushion, when used as a back for a car-seat, may be supported by the usual arms 17 which may be secured to the cushion by bolts 18 extending through the arms 17 and the end members of the frame and having nuts 19 on their inner ends.

It is obvious that when the use to which the cushion is to be put is such that only one side of the cushion is provided with a covering which is yieldingly supported and which should have the convex curvature, the extension of the form-piece on one side of the frame and the flange at the edge of that extension may be omitted. It will also be understood that the curvature of the flanges 10 longitudinally of the form-pieces may be varied according to the shape desired in the finished cushion.

Fig. 4 shows a form of cushion construction similar in all respects to that shown in the other figures except that instead of securing the form-pieces to the frame by riv-

ets extending through the form-pieces and the flanges at the sides of the end-members of the frame, these flanges are omitted and tacks 20 additional to those for securing the covering are driven through openings in the form-pieces and into the tacking strip to hold the form-pieces on the frame. Comparatively few of these tacks are sufficient as when the covering is in place, it and the tacks for securing it to the frame, hold the form-piece securely in place.

What I claim as new and desire to secure by Letters Patent is:

1. In a cushion, a rectangular metallic frame having end-members each provided with flanges at its edges turned inwardly of the frame and one on either side thereof, the connections between said flanges and the body portions of said end-members being rounding ones and the exterior surfaces of said flanges being curved in the direction of the length of the end-members, and a covering extending over said frame and secured at its edges thereto, said covering overlying said flanges and being shaped thereby, substantially as described.

2. In a cushion, a rectangular metallic frame having end-members, metallic form-pieces, secured to said members and each provided with a flange turned inwardly of the frame, the connections of said flanges with the body portions of the form-pieces being rounding ones and the exterior surfaces of the flanges being curved in the direction of the length of the form-pieces, and a covering extending over said frame and secured at its edges thereto, said covering overlying said flanges and being shaped thereby, substantially as described.

3. In a cushion, a rectangular metallic frame having end-members, metallic form-pieces secured to said members, each of said form-pieces being provided with flanges at its edges turned inwardly of the frame and one on either side thereof and said flanges being curved in the direction of the length of the form-pieces, and a covering extending over said frame and secured at its edges thereto, said covering overlying said flanges and being shaped thereby, substantially as described.

4. In a cushion, a rectangular metallic frame consisting of frame-members secured together at their ends, each of said members being a sheet-metal strip pressed into form to provide a groove on the outer side thereof extending lengthwise of the member, a tacking-strip secured in the groove in each of said members, a metallic form-piece secured to the tacking-strip on each of the end-members of the frame, each of said pieces having a flange at one of its lateral edges turned inwardly of the frame and curved in the direction of its length, a covering extending over said frame and overlying and shaped by said

flanges, and tacks securing the edges of said covering to said tacking-strips, substantially as described.

5. In a cushion, a rectangular metallic frame consisting of frame-members secured together at their ends, each of said frame-members being a sheet-metal strip pressed to provide a groove on the outer side thereof extending lengthwise of the member, a tacking-strip in the groove in each of said members, a metallic form-piece secured to the tacking-strip in each of the end-members of the frame, said form-pieces having flanges at

their lateral edges turned inwardly of the frame, one on either side thereof and curved 15 in the direction of their length, a covering extending over both sides of the frame and overlying and shaped by said flanges, and tacks securing the edges of the covering to said strips, substantially as described. 20

This specification signed and witnessed

this 24th day of April, 1906.

EDWARD G. BUDD.
